UNITED STATES PATENT OFFICE.

ESMOND M. SMITH, OF NEW YORK, N. Y., ASSIGNOR OF ONE-HALF TO LEOPOLD PLAUT
AND ONE-HALF TO HERMAN PLAUT, BOTH OF NEW YORK, N. Y.

LIGHTING-FIXTURE.

1,240,505.

Specification of Letters Patent. Patented Sept. 18, 1917.

Application filed January 18, 1917. Serial No. 143,610.

To all whom it may concern:

Be it known that I, EDMOND M. SMITH, a citizen of the United States, resident of the city, county, and State of New York, have invented a certain new and useful Lighting-Fixture, of which the following is a specification.

This invention relates to improvements in fixtures for use in indirect, and for combined direct and indirect systems of illumination, and for analogous purposes.

In systems of indirect or semi-indirect illumination in which the light or a portion thereof is cast upon the ceiling whence it is reflected halations or areas of high illumination or shadows of intervening objects are cast upon the ceiling and render such illumination uneven and unsightly.

The objects of my invention are:-

First: to diffuse the illumination and to avoid halation and casting of shadows.

Second: to improve the facilities for cleaning the fixture.

Third: to render the lamp more accessible.

Fourth: to reduce the cost and improve the appearance of the finished structure.

These and further objects will more fully appear from the following specification and accompanying drawings considered together or separately:-

In the drawings

Figure 1 is a side elevation of a shade embodying my invention, showing the same in connection with an artificial ceiling.

Fig. 2 is a plan view of the shade.

Fig. 3 is a sectional view thereof, taken on the line 3, 3 of Fig. 2.

Fig. 4 is a side view of a modification and

Fig. 5 is a side view of another modification.

In all of the views like parts are designated by the same reference characters.

Referring to the drawings, in the embodiment chosen for illustration, the improved shade 1 includes a bowl or globe 2, which is adapted to surround and inclose the lamp 3. The lamp is supported by means of my suitable device, such as a stem or socket 4, in proper position within the bowl. The bowl is provided with a neck 5, which surrounds the base of the lamp or the stem or socket as depends upon the character of the structure. The lamp support is

adjustable for the purpose of positioning the lamp and the center of illumination relatively to the neck and bowl for a purpose to be hereinafter described. The neck is provided with a rim 6, by means of which it may be supported. The illustration shows that it is supported from a collar 7 by means of the screws 8. In connection with the collar is shown an artificial ceiling 9, but the same is not necessary where the device is supported in proper relation to a ceiling 9^a (see Fig. 4) which will properly reflect the light cast upward to it in the manner hereinafter described. The neck and bowl are connected by a top 10.

My improved shade comprising a bowl, neck and top is preferably made of a single piece of transparent or crystal glass. The lower end of the neck is on a plane below the upper edge of the bowl. The bowl and the neck may be made of semi-transparent reflecting-diffusing character, preferably by being coated with a suitable enamel or other substance, which will give them a translucent effect. This will allow direct passage, through the neck and bowl, of the rays of light from the lamp but such rays will become much diffused. This coating is preferably sprayed on the outsides of the bowl and neck. The structure is then baked in the usual enameling oven so that the enameled surface becomes part of the glass. The coating on the bowl is indicated by 11 and upon the neck by the character 12. The coating 11 should preferably extend to the upper edge of the bowl as at *a* and the coating 12 on the neck extends downward below the same horizontal plane to the point indicated by *b*. The top 10 from the point *a* to the point *b* is transparent, hence the light reflected from the surfaces 11 and 12 will pass through this transparent portion hereinafter described, and such light will be reflected downwardly from the ceiling. The inner surfaces of the neck and bowl are of a reflecting-diffusing character so that rays of light reflected from such surfaces will be scattered or diffused and will issue from the shade through the transparent top 10 in such a manner that there will be no halation, shadows will be eliminated, and the illumination on the ceiling and that reflected therefrom will be uniform. The reflecting inner surfaces of the neck and bowl are made dif-

fusing by forming them of ribs or corrugations, by sand blasting, acid etching, or by any other means.

While the inner surface of the neck may be of diffusing character this is not necessary for the reason that all light reflected from that surface must be re-reflected and diffused by the inner surface of the bowl before it passes through the top 10.

10 I prefer to make the neck 5 of a greater density than the bowl for a purpose to be hereinafter described.

The neck 5 should be of sufficient size to permit passage of the lamp so that the shade 15 may be removed when desired and the lamp thereby reached.

There being no open portions of the shade permitting the admission of dirt or dust, the same need be cleaned on the outside only.

20 The device is very cheap of manufacture, is not likely to get out of order and is extremely pleasing in appearance.

If desired the device may be constructed of a bowl or globe 2 composed of so-called 25 opal glass or other translucent material, a neck 5 of similar material, and a top 10 of transparent glass. The parts may be secured together by cementing, welding, fusing or in any other desired manner.

30 As shown in Fig. 5 the neck 5 may be of a length just sufficient to permit of its attachment to its supporting means, and may be so short that its upper edge will come below the level of the rim of the bowl 2. In this 35 situation the neck is rendered translucent or opaque, as the case may be to the same point as that shown in Fig. 3.

Instead of being semi-transparent or translucent the bowl 2 and neck 5 may be 40 coated with an opaque substance and the fixture used for indirect lighting. When so used I prefer to silver the outer surface of the bowl and neck and then coat the silver with paint, bronze or other suitable material. The outer surfaces of the bowl and neck may be highly reflective. The light reflected from the inner surfaces of the bowl and neck will be diffused by the roughened surfaces. All of the light issuing from the 50 bowl through the transparent top will be diffused and reflected from the interior surface of the bowl. Some of such light will be re-reflected from the outer surface of the neck. The greater portion of the light will 55 be reflected from the ceiling and again reflected from surrounding objects to the exterior surface of the bowl whence it will be again reflected.

If desired the bowl may be opaque and the 60 neck translucent, or the neck may be opaque and the bowl translucent, but in all cases the top 10 is transparent.

The center of illumination is so positioned relatively to the lower edge of the

opaque or translucent portion of the neck 65 that any direct rays of light passing below such lower edge will be intercepted by the opaque or translucent part of the bowl and no light except that reflected and diffused by the inner surface of the bowl will pass 70 through the transparent top 10. For this reason the lamp support should be adjustable to allow for variations in lamps.

As the neck is nearer the source of illumination than the bowl it may be desirable, 75 when the parts are translucent, to make the neck of a greater density than the bowl so that both parts will have the same appearance when illuminated.

In accordance with the provisions of the 80 patent statutes I have described the principle of my invention, together with the apparatus which I now consider to represent the best embodiment thereof, but I desire to have it understood that the apparatus 85 shown is merely illustrative, and that the invention may be carried out in other ways.

Having now described my invention what I claim as new and desire to secure by Letters Patent, is:

1. A lighting fixture comprising a shade for an electric lamp; said shade comprising a bowl, a neck open at the top for the insertion of the lamp, said neck being of less diameter than the bowl, a top connecting the 95 bowl and neck, said shade being composed of a single piece of transparent glass; the interior surfaces of the neck and bowl being so treated as to render them diffusive; the exterior surfaces of the neck and bowl being coated with a material to render the neck and bowl non-transparent and to render the interior surfaces of the neck and bowl 100 highly reflective.

2. A lighting fixture comprising a shade for an electric lamp, having a bowl adapted to inclose the lamp, a neck adapted to support the bowl, and a top connecting the upper edge of the bowl with the neck, the lower end of said neck being on a plane below the upper edge of said bowl, said shade being made of a single piece of transparent glass, the interior surfaces of said bowl and said neck being highly reflective and diffusive, the exterior surfaces of said bowl and neck being coated to make the same non-transparent, there being a surface opposed to the top to receive light reflected from the bowl, the lamp being so situated relatively to the lower edge of the neck and the upper edge of the bowl that no direct rays will fall on the surface.

3. A lighting fixture comprising a shade for an electric lamp, having a bowl and a neck adapted to inclose the lamp and a top connecting the upper edge of the bowl and lower edge of the neck, said shade being made of a single piece of

transparent glass, the exteriors of said bowl and neck being treated to render them non-transparent, the lower edge of the neck being so situated relatively to the upper edge of the bowl that direct rays of light from the lamp will be prevented from passing through the transparent top, the neck being so situated that all the light reflected from its interior surface will be directed into the bowl and being positioned relatively to the concave surface of the bowl that diffused light from such surface will be reflected to the exterior of the neck,

there being a surface opposed to the transparent top to receive diffused light reflected from the interior of the bowl, the exteriors of the neck and bowl being highly reflective so as to re-reflect the light reflected to them by surrounding objects.

This specification signed and witnessed this twelfth day of January, 1917.
